UNITED STATES PATENT OFFICE.

FRANK LE BLOND, OF JOLIET, ILLINOIS.

APPARATUS FOR LOADING AND UNLOADING INGOTS.

SPECIFICATION forming part of Letters Patent No. 360,028, dated March 29, 1887.

Application filed December 29, 1886. Serial No. 222,936. (No model.)

To all whom it may concern:

Be it known that I, FRANK LE BLOND, a citizen of the United States of America, residing at Joliet, in the county of Will and 5 State of Illinois, have invented certain new and useful Improvements in an Apparatus for Loading and Unloading Ingots, of which the following is a specification, reference being had therein to the accompanying drawings.

10 This invention consists in certain improvements in an apparatus for loading and unloading ingots on cars in a steel-converting mill, the construction and operation of which is fully set forth and explained in the following 15 specification and claims, reference being had to the drawings hereto annexed, and the letters and figures of reference thereon, making a part of this specification, in which—

Figure 1 is a plan view of the pit of a steel- 20 converting mill, showing the arrangement of the ingot-molds on their lifting base-plates, and also showing a track and cars thereon arranged on a corresponding curve with that in which the molds are set, and leading from the bank 25 into the pit. Figs. 2 and 3 are detail side views showing the arrangement of the ingot-molds on their base-plates and the mechanism for lifting and tilting the molds and the ingots therein. Fig. 4 is a sectional elevation of the 30 pit shown in Fig. 1, showing the mechanism for loading ingots and their molds on cars. Fig. 5 is a detail rear view of a pair of ingot-molds resting on a base-plate, and showing the forked arms of a piston attached to the lower 35 side of said plate for lifting and tilting it and the molds thereon. Fig. 6 is a cross-sectional view of the pit-track upon which the cars travel. Fig. 7 is a perspective view of one of the base-plates for supporting the ingot-molds. 40 Fig. 8 is a top plan view of the mechanism for removing ingots from the ingot-molds; and Fig. 9 is a side elevation of one of the hydraulic cylinders and an end view of a track and guideway upon which said cylinder slides, it being a portion of the mechanism for removing 45 the ingots from the molds.

Referring to the drawings, A represents the pit of a steel-converting mill.

M represents the converting-vessels.

50 L is the ladle for carrying the molten metal from the converting-vessel to the ingot-molds.

B is a set of ingot-molds arranged in a semi-circle convenient for the ladle L.

P are base-plates for supporting and forming each the bottom of a pair of molds.

F are frames for the base-plates to rest upon.

H are hydraulic cylinders, one arranged underneath each base-plate in a pit and connected with the base-plate above through the medium of the two arms G' G' and the piston 60 G, as shown in Figs. 2, 3, 4, and 5. The said plates P are provided on their lower rear side with two pairs of ear-lugs, a a, as shown in said figures, to which the arms G' G' of the piston G are hinged by the bolts d. The said 65 cylinders stand in an inclined position, as shown in Figs. 3 and 4, so that when the piston is down and the plate P lies horizontally on its frame F and covers the pit holding said cylinders, as shown in Figs. 2, 4, and 5, the 70 arm G' will not be engaged with said plate.

C represents a hydraulic crane for operating the chain C', for assisting to lift and load the ingot-molds B.

T represents a plate having grooves T', forming the track for the cars D, which track extends in the pit and is curved to conform to the position of the molds B, and lies adjacent thereto. The track is made of a plate of metal, to render it easy to remove any spilling 80 metal that may fall on it, as it will not stick to the plate, as it might on and around ordinary rails.

The upper face of the base-plates P is provided with two raised portions, P' P', as shown 85 in Fig. 7, forming the bottom of a pair of molds, which set down over them, as shown in Fig. 5. These raised portions P' are convex, so they will form a concave surface on the lower end of the ingot when molded, so that 90 when the ingot is bloomed its lower concaved end will be square instead of convex.

O are lugs on the upper surface of said plates, for preventing the mold from sliding off while being tilted over and loaded on the car. In 95 Fig. 1 eight base-plates P are shown, and sixteen molds—two for each plate.

It is intended that the ladle L will hold one heat of the converting-vessel M, being enough metal to fill eight molds at each heat, so that 100 while eight are being filled the remaining eight may be removed with their ingots, and

after having the ingots removed be returned in time for the next heat. When eight molds are filled and the metal is set, so that it will not run from the mold, and it is desired to remove the molds for the purpose of removing the ingots therefrom, while they are yet hot the chain C' (which is branched) hooks to two molds resting on a single base-plate. Pressure is then let on both the hydraulic crane C and the hydraulic cylinder H simultaneously. As the piston G moves upward, the rear side of the base-plate P will be lifted first, and the plate and molds on it will tilt forward until the arm G² of the cylinder will engage with the forward under side of said plate, as shown in Fig. 3, to support that side of the said plate in that position. Further movement of said piston G lifts said base-plate and the two molds resting on it until said plate will be about on a level with the car D; as shown in dotted lines in Fig. 4. When it reaches such position, said piston is arrested and holds said plate stationary, while the hydraulic crane is caused to lower the chain C', and permit the mold to be laid over on the car to load it, as shown in Figs. 1 and 4, so that it can be removed from the pit to have the ingot removed, and then be returned and replaced on the base-plates by operating said crane and cylinder in a reverse manner. By this means the ingot is prevented from falling from its mold while the mold is being hoisted from the pit, and can be removed from the pit much sooner than without the use of these base-plates.

The cars D are small enough to pass under the ladle L, so as not to interfere with it while it is filling molds. The hydraulic cylinders H are of the ordinary pattern, and hence no further description or illustration of them is necessary. The ordinary tracks, T, lead from the pit up on the bank to the mechanism for removing the ingots from the molds, which mechanism is shown in Figs. 8 and 9. In said figures W W are a pair of guideways, upon which a hydraulic cylinder, R, is arranged to move horizontally by means of its connection with the piston of the hydraulic cylinder R'. The water-pipes S and S', and also S² and S³, of the cylinder R are telescopically connected, so that said cylinder may be thus moved.

In operation, the cars D, loaded with molds B, containing the ingots, are brought alongside of a platform divided into stalls J by means of partitions J', as shown in Fig. 8, and in such position that the end of the mold will be opposite a partition, and so that the piston of the cylinder R will stand opposite the end of an ingot. Pressure being let in said cylinder will cause said piston to drive the ingot I out of its mold and deposit it in a stall J, as shown in Fig. 8, the mold being held meanwhile by its contact with said platform and partitions.

The cylinder R' is provided with the feed-pipes M and M', to admit pressure at either end to move the cylinder R, as stated.

In Fig. 8 the molds in one car are shown as having had their ingots I removed, while those on the other car are in the process of being removed. By this means of removing the ingots from their molds it becomes unnecessary to remove the molds from the cars during such operation. By this arrangement of the parts described the necessity of having to wait until the ingots cool and shrink enough to be easily removed from the molds is obviated, as the ingots are taken from the pit when very hot and forcibly ejected from the molds, and thus their first heat is largely retained and utilized at their next heat. The molds are returned to the pit while they are yet quite hot, and the next heat from the converting-vessel is poured into them before they get cold, so that the difficulty of chilling the sides of the ingots is obviated, as would be the case were the molds cold when poured, and thus in working the several parts of this machine conjointly the result desired is accomplished.

Having thus described my invention, what I claim as new, and desire to secure by Letters Patent, is as follows, to wit:

1. In combination with the base-plate P, the piston G of the cylinder H, terminating in two rear diverging arms, G' G', hinged to the rear under side of said plate, and a forward-extending arm, G², arranged a little distance from said plate, when said plate is lowered to a resting position, and adapted to engage and support the forward side of said plate after the arms G' have raised it to an inclined position, substantially as and for the purpose set forth.

2. In the apparatus shown and described, the pistons G of cylinders H, terminating in the diverging arms G' G' and G², in combination with said cylinders and the base-plate P, substantially as and for the purpose set forth.

3. In an apparatus for loading ingots and their molds on cars, a base-plate forming the support for said molds, in combination with the piston of a hydraulic cylinder, hinged to and arranged in an inclined position below said plate in such manner as to tilt forward and lift the ingots and molds on said plate when pressure is applied to said cylinder, and a hydraulic crane for steadyng and lowering the upper end of said ingot and mold on a car, in the manner substantially as set forth.

4. In a steel-converting mill, a series of ingot-mold-supporting base-plates arranged in a semicircle within and adjacent to the bank-walls of the pit and resting upon frames for supporting said molds in a perpendicular position, in combination with the pistons of a series of hydraulic cylinders hinged to and arranged below said base-plates, and the grapple-chain of a hydraulic crane, operating as set forth, and a car-track arranged descending from the bank to said pit, and adjacent to said base-plates, for supporting the cars upon

which the ingots and molds are loaded, substantially as and for the purpose specified.

5. In the apparatus shown and described, the combination, with a hoisting-crane, of the base-plates P, hydraulic cylinders H, and forked pistons G of said cylinders, substantially as and for the purpose set forth.

6. In the apparatus shown and described, the base-plate P, having the lugs O and raised portions P' on its upper surface, and the ear-lugs a a, depending from its lower surface, in combination with forked piston G and cylinder

H, substantially as and for the purpose specified.

7. In the apparatus shown and described, the combination of sliding cylinder R, guides W W, piston Z, pipes S S' S² S³ M M', cylinder R', piston t, and platform J, having the partitions J', substantially as and for the purpose set forth.

FRANK LE BLOND.
